(57) **CLAIM**

The rope or cable hook for trailers or trucks, as shown and described.

DESCRIPTION

FIG. 1 is a perspective view of a rope or cable hook for trailers or trucks showing my new design;

FIG. 2 is a bottom view thereof;

FIG. 3 is a right side elevational view thereof, with the left side view being a mirror image of the right side view;

FIG. 4 is a top view thereof;

FIG. 5 is a rear view thereof;

FIG. 6 is a front view thereof.

FIG. 7 is a front view of a second embodiment of a rope or cable hook for trailers or trucks showing my new design;

FIG. 8 is a top view thereof;

FIG. 9 is a side elevational view of a third embodiment of a rope or cable hook for trailers or trucks showing my new design; and,

FIG. 10 is a side elevational view of the second embodiment shown in FIGS. 7 and 8.

The broken lines shown are for illustrative purposes only and form no part of the claimed design.
